STEAM-EJECTOR.

1,079,134.

Specification of Letters Patent.

Patented Nov. 18, 1913.

Application filed April 9, 1913. Serial No. 760,081.

To all whom it may concern:

Be it known that I, MAURICE LEBLANC, a citizen of the Republic of France, residing in Val sur Seine par Croissy, Seine-et-Oise, France, have invented certain new and useful Improvements in Steam-Ejectors, of which the following is a specification.

This invention relates to steam ejectors and has for its object to provide an apparatus of this nature which may be both started and operated under the best conditions of steam consumption and efficiency.

It is well known that the dimensioning of certain parts of an ejector designed to with-
draw a fluid in an inclosed space at the pressure p and to force it into an inclosed space at the pressure P , should vary with the pressures p and P , also that the cross-section of the neck of the nozzles into which the motive steam is projected should vary with the initial pressure of the steam. In general the ejector should produce at starting the difference of pressure which it is required to maintain afterward. This difference increases gradually from zero until the pressures p and P have acquired their normal values.

If the dimensioning of an ejector has been carried out with a view to obtaining the best possible efficiency during normal running, the ejector cannot be properly dimensioned for starting under favorable conditions, be-

cause the ratio $\frac{P}{p}$ which at starting is equal

to 1 ought to be greater in normal running. Again the ejector does not start if the nor-

mal value of the ratio $\frac{P}{p}$ exceeds a certain limit.

In order to cause the ejector to start, according to one method its dimensions are temporarily varied and are brought gradually to their normal values when once the starting is obtained. According to another method the pressures p and P are artificially varied at starting and the normal dimensions of the ejector are made suitable for the new pressures thus obtained. Several arrangements for carrying out both of these methods have already been patented by the applicant.

The present invention relates to an im-

proved ejector which is started by the first method above mentioned and which is characterized by the fact that the variation of its dimensions and output is effected by varying the number, distribution, and output of the several jets of motive steam.

The only movable or flexible parts which this improved ejector requires are simple valves the manipulation of which suffices to obtain the desired variations of dimensions and output. The arrangements for regulating this improved apparatus are therefore very simple and experience has shown that they are completely effective.

In order that the invention may be clearly understood a practical embodiment of the same will now be described with reference to the accompanying drawings in which—

Figure 1 shows diagrammatically the essential parts of the improved ejector arranged according to this invention, and Fig. 2 illustrates a modification.

Referring to Fig. 1 of the drawings, motive steam is supplied to the space A where the steam jets act upon the fluid to be withdrawn, by a large number of converging-diverging nozzles such as those represented at B_1, B_2, B_3, B_4 . These nozzles are distributed in concentric crowns which are shown in the drawing as being four in number. In order to simplify the description it will be supposed that the exit orifices of these nozzles all have the same cross-section; but it is to be understood that this is not necessary in practice. The fluid to be withdrawn flows into the space A through a pipe C, while opposite the exit orifices of the nozzles is the opening of a converging-diverging diffuser D which opens into the space into which it is desired to force the fluid which has been withdrawn by the pipe C.

In the improved ejector all the nozzles B of the same crown are fed with steam from one steam chamber which is separate from any other steam chamber, these steam chambers, to the number of four as shown in Fig. 1, corresponding to the four concentric crowns of nozzles, being represented at E_1, E_2, E_3, E_4 . The motive steam is supplied to each of these steam chambers by one of the pipes F_1, F_2, F_3, F_4 , and each of these pipes is connected to the main steam pipe G, and is provided with a valve H_1, H_2, H_3, H_4 . The steam pressure prevailing in each pipe

F beyond the corresponding valve H is indicated by the corresponding steam gage I₁, I₂, I₃, I₄.

By means of the connections and valves above described steam at any desired pressure (up to that of the steam in the main pipe G) can be supplied to the nozzles of any one of the crowns and this pressure may be different from the pressure of the steam supplied to the nozzles of any other crown.

The neck, that is, the part of the nozzle where the converging portion meets with the diverging portion, is given the same cross-section in the case of all the nozzles of one and the same crown, but the cross-section of the necks of one crown of nozzles is made different from that of the necks of any other crown of nozzles. The applicant has found by experiment that there is an advantage in giving the greatest cross-section to the necks of the nozzles of the outer crown and in reducing this cross-section proportionally to the reduction of the diameters of the successive crowns.

In normal running all the nozzles of the ejector will be in operation and as they are all supposed to have exit orifices of the same cross-section they should therefore have substantially the same output. Hence the various nozzles should be fed with steam at a lower pressure in proportion as their necks have a greater cross-section. Under these conditions the pointers of the steam gages I₁, I₂, I₃, I₄, will occupy different positions as shown in the drawing; the correct steam pressure for each crown of nozzles may be marked on the dials of the steam gages.

The exit orifices of the nozzles should always be given such cross-sections that, during normal running, the steam issues from them with a pressure somewhat higher than the pressure p which it is desired to maintain in the space A. At starting the pressure in this space will generally be equal to P and, to simplify the description, this pressure will be supposed to be constant. In order that the steam may issue at a high speed from the nozzles it is necessary that its pressure should not drop at that point below the pressure P, as is demonstrated in the work of Stodola on "Steam turbines".

The above condition will be approximately fulfilled in practice by sending all the available steam into the nozzles of the outer crown alone, that is, by opening wide the valve H₁ and closing all the others, as their necks have a cross-section greater than that of the necks of the other nozzles. It has been found that under these conditions the pressure p drops and acquires a value p_1 smaller than the pressure P. The valve H₁ is then gradually closed to some extent and the valve H₂ is opened, in such a manner that all the available steam continues to pass through the nozzles of the two first crowns

and this operation is continued until the pressures indicated by the gages I₁ and I₂ show that the nozzles of the said two crowns have the same output. It is then observed that the pressure in the space A acquires a new value p_2 lower than the value p_1 , and so on.

In the above described operation ejectors having only one crown, two crowns, and so on, of nozzles are successively brought into use but always consuming the same quantity of motive steam, that is, the ejector having one crown is gradually transformed into an ejector having two crowns, and so on, in proportion as the pressure is reduced in the space A; hence the output of the nozzles in service is greater in proportion as they issue into a medium at a higher pressure thus enabling the jets of steam issuing from them to have a speed sufficient to pass the diffuser without being too much expanded and without occupying all the cross-section of the diffuser, which otherwise would render the flow of the withdrawn fluid impossible. To facilitate the operations a suitable number of marks may be provided upon the dials of the steam gages to indicate the positions which their pointers ought to occupy according as there are one, two, three or four crowns in service.

In addition to the arrangement of nozzles described above, the applicant has also tested an ejector in which the steam was first supplied to the central nozzles, which for this purpose were given necks of a large cross-section and in some cases this cross-section was made variable by means of movable needles. This arrangement however has not furnished such good results as that first described above. It is probable that the withdrawing action of the jet projected by the central nozzles combined with the retarding action of the walls produces a whirling ring which incloses the jet and takes work from it thus causing its rapid expansion. This phenomenon is not produced in the interior of the hollow jet constituted by the assemblage of the jets issuing from the nozzles of the exterior crowns, as the retarding action of the walls does not appear to have any effect in the interior of this hollow jet.

It has been found that in order to start the improved ejector it is generally sufficient to send the steam only into the nozzles of the exterior crown; when the pressure has once been brought to the value p_1 , if the steam is so regulated as to bring the pointer of the gage I₁ to the position corresponding to normal running the pressure in the space A takes a new value p'_1 smaller than p_1 and sufficiently low to enable the ejector to definitely start and be brought to normal running by opening simultaneously the valves H₂, H₃, and H₄. Owing to this fact the applicant has developed the modification

shown in Fig. 2, which is a simpler construction than that shown in Fig. 1, as it only comprises two separate steam supply pipes although the nozzles may be distributed in 5 any number of concentric crowns. This form of the improved ejector generally starts easily and all its interior crowns of nozzles connected in parallel may have necks of the same cross-section provided that they 10 have exit orifices of the same cross-section.

10 The invention is not limited to the precise number or arrangement of separate steam supply pipes described hereinabove and illustrated in the drawings, as it is evident that 15 any desired number of such separate steam supplies may be employed and these may be arranged to feed each, or any desired number, of the nozzles of one or more concentric crowns, without departing from the scope 20 of the invention.

What is claimed is:

1. A steam ejector comprising a plurality of separate steam chambers, a group of nozzles secured in each steam chamber for projecting steam upon the fluid to be withdrawn, and means for supplying steam at different pressures to the several steam chambers. 25

2. A steam ejector comprising a plurality of coaxially arranged separate steam chambers, a separate group of nozzles fed from each steam chamber for projecting the motive steam upon the fluid to be withdrawn, a pipe connecting each steam chamber with 30 a main steam supply, and means in each pipe

for independently controlling the supply of steam to the corresponding steam chamber.

3. In a steam ejector, a plurality of coaxially arranged steam chambers, one or more coaxial rings of converging-diverging nozzles grouped in each steam chamber, the ratio 40

$$\frac{\text{cross-section of neck}}{\text{cross-section of exit orifice}}$$

45 of the nozzles being constant within each group but different in the different groups, steam pipes for separately supplying steam to each steam chamber, and means for varying the output of the nozzles with variation 50 in the pressure of the medium into which they exhaust.

4. In a steam ejector, a plurality of separate steam chambers, a plurality of nozzles grouped in each steam chamber, the nozzles 55 of one group being differently dimensioned relatively to those of another group, a separate steam pipe for supplying steam to each steam chamber, a pressure regulating valve in each steam pipe, and means for indicating 60 the most favorable pressure of steam to supply to each group of nozzles under the various conditions of starting and running.

In witness whereof, I have hereunto signed my name in the presence of two subscribing 65 witnesses.

MAURICE LEBLANC.
